HYDROXYARYL-ALKYL AND ARALKYL
SULPHIDES

Ellis Miller, Philadelphia, Pa., assignor to Sharp & Dohme, Inc., Philadelphia, Pa., a corporation of Maryland

No Drawing. Application September 25, 1933,
Serial No. 690,944

12 Claims. (Cl. 260—150)

This invention relates to new hydroxyaryl alkyl and aralkyl sulphides and methods of preparing hydroxyaryl-alkyl and -aralkyl sulphides. It includes hydroxyphenyl-alkyl sulphides which have 5 three or four or more carbon atoms in the side chain and which have a high phenol coefficient and valuable therapeutic properties. It also includes the hydroxyaryl-aralkyl sulphides. The invention relates particularly to the hydroxy-10 phenyl-butyl -amyl and -hexyl sulphides and the hydroxyphenyl-aralkyl sulphides.

In the following table certain of these compounds are listed together with their chemical properties. It will be observed that the higher 15 hydroxyphenyl-alkyl sulphides, viz., those having three, four, five and six carbon atoms in the side chain have a higher phenol coefficient than those members of the series which have but one or two carbon atoms in the side chain.

sulphide. An aralkyl halide may be employed to form an aralkyl sulphide. In the second method an ether of an aryl diazonium compound is coupled with an alkyl or aralkyl mercaptan, the diazo compound is heated to remove the nitrogen and unite the sulphur directly with the aryl group, and the compound then de-etherified. The compounds prepared by either method may be purified for medicinal use by recrystallization from organic solvents. The two methods will be 10 exemplified by detailed descriptions of the preparation of para-hydroxyphenyl-n-butyl sulphide.

Example 1

20 parts of sodium hydroxide are partially dissolved in 50 parts of methyl alcohol. To this is added a solution of 58.3 parts of thiohydroquinone, $C_6H_4(OH)(SH)$, in 50 parts of methyl alcohol. The mixture is stirred and then 68 parts

		Phenol coefficient	Boiling point, C.	Melting point, C.	
25	1	8	113° (6 mm.)		20
	2	10	153-5° (13 mm.)	41°	25
	3	36	150-3° (5-6 mm.)	37°	
	4	77	166-8° (7 mm.)	49-50°	15
30	5	120	175-8° (8-10 mm.)	59°	
	6		164-68° (3-4 mm.)		30
	7		194-96° (16 mm.)		
	8	20	178-80° (5 mm.)	60°	
35	9	61	150-2° (13 mm.)		35
	10	30	159-62° (10 mm.)		
	11	30	150-2° (3 mm.)		
40			220-5° (15 mm.)	104°	40
		40	127-140° (4 mm.)		

40 The -isopropyl and -isobutyl sulphides are liquid. The phenol coefficient of p-hydroxyphenyl-n-hexyl sulphide and p-hydroxyphenyl-benzyl sulphide measured by the usual procedure was 0, i. e., a saturated solution was inert. When these products were dissolved 1:1000 in N/100 sodium hydroxide and further dilutions made with water, the values 230 and 20 were obtained. The solubility of the p-hydroxy-phenyl-n-hexyl sulphide 45 is apparently less than 1:10,000 in water.

45 There are two methods of preparing these compounds in sufficiently pure form for medicinal use. In the first method thiohydroquinone or other hydroxythiophenol is caused to react with 50 an alkyl halide to form the hydroxyaryl alkyl

55 of n-butyl bromide are added during the course of fifteen minutes. Reaction sets in at once and proceeds vigorously with the evolution of heat and the formation of a voluminous precipitate of sodium bromide. The resulting mass is refluxed for about an hour. It is allowed to cool and is then filtered. The filtrate is distilled to remove methyl alcohol which is recovered and may be reused. The residual oil is then washed with water and it may be extracted with benzene and distilled in vacuo. The major fraction of the para-hydroxyphenyl-butyl sulphide which distills over boils at 165-8° C. (7 mm.). It solidifies on standing to a white crystalline mass which 55

when recrystallized from benzene-ligroin mixture melts at 49-50° C.

By using other alkyl halides, e. g., propyl, amyl, hexyl, isopropyl, isobutyl, isoamyl or isoheptyl bromide or aralkyl halides, e. g., benzyl, phenylethyl, tolylethyl or naphthylmethyl bromide instead of the n-butyl bromide of this example, the corresponding para compounds may be prepared. Starting with m-C₆H₄(OH) (SH), meta alkyl and 10 aralkyl compounds may be prepared. By starting with a substituted thio monohydroxy phenol, for example, the tolyl derivative, other hydroxy aryl-alkyl or aralkyl sulphides are obtained.

Example 2

15 68.5 parts of para-phenetedine,
 $\text{NH}_2\text{---C}_6\text{H}_4\text{---OC}_2\text{H}_5$

are dissolved in an excess of 10 per cent hydrochloric acid. This solution is cooled below 15° C. and diazotized by the gradual addition of 35 parts of sodium nitrite in aqueous solution while the temperature is maintained at 15-20° C. by means of ice.

25 The diazo solution is then run slowly beneath the surface of a hot solution of 49.5 parts of n-butyl-mercaptan C₄H₉SH, in 400 parts of 20% caustic soda, care being taken to stir the mixture vigorously and maintain the temperature at 30 70-75° C. When all the diazo solution is in, the temperature is raised to 90° C. and this is maintained until no further evolution of nitrogen is observed. The solution is then allowed to cool down to room temperature and is acidified with 35 concentrated hydrochloric acid. A heavy black oil separates. The oil is washed first with dilute hydrochloric acid and then with water and is distilled in vacuo yielding an intermediate product, viz., paraethoxyphenyl butyl sulphide with a boiling point of about 150-160° C. (12 mm.). This 40 ether is then de-ethylated by refluxing at 75-85° C. for a number of hours with an excess of 20% hydrobromic acid in glacial acetic acid. When the de-ethylation is practically complete the excess hydrobromic-acetic acid mixture is 45 removed by vacuum distillation. Ester present in the residual oil is then hydrolyzed by refluxing with 10 per cent caustic soda dissolved in 25% alcohol. The alcohol is then distilled off leaving in solution the sodium salt of para-hydroxyphenyl-n-butyl sulphide. This solution is extracted a number of times with benzene to remove 50 any un-de-ethylated product and the water solution is acidified with hydrochloric acid. The oil which separates is taken up with benzene, washed 55 with water and distilled in vacuo. A white crystalline product melting at 48° C. is obtained. Recrystallized from benzene-ligroin mixture, it melts at 49-50° C.

60 Other alkyl mercaptans may be employed instead of n-butyl mercaptan to prepare other para compounds, e. g., normal and isopropyl, amyl and hexyl mercaptans and isobutyl mercaptans. Aralkyl compounds may be made by using aralkyl mercaptans such as normal phenyl and naphthyl methyl and ethyl, etc. mercaptans. Starting with 65 meta NH₂—C₆H₄—OC₂H₅ or other ether, meta

hydroxyaryl-alkyl or -aralkyl sulphides may be prepared. By starting with a substituted amino aryl ether, such as an amino tolyl ether other hydroxyaryl-alkyl and aralkyl sulphides are obtained.

5 The new compounds of this invention are valuable as antiseptics and have a relatively high phenol coefficient as compared with para hydroxyphenyl-ethyl sulphide.

I claim:

1. Antiseptics having the formula

15 where one X stands for OH and the other stands for hydrogen and R is a member of the group consisting of aralkyl radicals and alkyl radicals containing three or more carbon atoms.

2. Para-hydroxyphenyl-alkyl sulphides having 20 at least three carbon atoms in the alkyl group and having a high phenol coefficient.

3. Para-hydroxyphenyl-butyl sulphides.

4. Para-hydroxyphenyl-amyl sulphides.

5. Para-hydroxyphenyl-hexyl sulphides.

6. Para-hydroxyphenyl-n-butyl sulphide.

7. Para-hydroxyphenyl-n-amyl sulphide.

8. Para-hydroxyphenyl-n-hexyl sulphide.

9. The method of preparing compounds of the 30 group consisting of hydroxy aryl-alkyl and -aralkyl sulphides which comprises reacting in the presence of an alkali an halide from the group consisting of alkyl and aralkyl halides with a compound having the formula HO—R—SH where R is an aryl group.

10. The method of preparing para-hydroxyphenyl-alkyl sulphides which comprises reacting 35 in the presence of an alkali an alkyl bromide in the presence of an alkali.

11. The method of preparing para-hydroxyphenyl-alkyl sulphides which comprises dissolving 40 sodium hydroxide and thiohydroquinone in a solvent, gradually adding an alkyl bromide thereto, maintaining the temperature at the refluxing point at least until the reaction nears completion, filtering off the sodium bromide which has been precipitated and then recovering para-hydroxyphenyl-alkyl sulphide from the residue.

12. The method of preparing para-hydroxyphenyl-n-butyl sulphide which comprises dissolving 45 sodium hydroxide and slightly more than an equivalent amount of thiohydroquinone in a suitable organic solvent, adding n-butyl bromide to the solution, the sodium hydroxide and the bromide being used in equimolecular proportions and the bromide being stirred into the solution gradually while reaction sets in which forms a voluminous precipitate of sodium bromide, the mass being kept hot until the preparation of the para-hydroxyphenyl-butyl sulphide has reached 50 substantial completion, then filtering off sodium bromide which has been formed, extracting the remaining filtrate, and distilling para-hydroxyphenyl-n-butyl sulphide from the extract.

55 ELLIS MILLER.
